INVENTOR

BY *G. Woodward*
ATTORNEY

UNITED STATES PATENT OFFICE

HENRY D'OLIER, JR., OF BRIDGEPORT, CONNECTICUT

RIGID BAILED CONNECTER AND CONNECTER SOCKET

Application filed September 30, 1929. Serial No. 396,214.

This invention relates to electrical sockets, and more particularly to lamp-sockets, this expression being used however as a broad designation for sockets adapted to receive 5 lamps and many other articles of the various types for which such sockets are used in electrical circuits.

My present application is in part a division of my application Serial No. 189,058 filed 10 May 5, 1927, and in part a continuation thereof, certain improvements in structure being also disclosed and claimed.

There is a present tendency to increase the size of individual incandescent electrical 15 lamps, with an attendant increase in weight of the lighting unit, comprising the lamp, its shade and fittings, so that a heavy suspended unit of this character can no longer depend with safety for its support on the ordinary insulated conductors which have 20 sufficed for the lighter units.

These large units also require greater care, and could be more readily cleaned and otherwise handled were they readily detachable, 25 with their sockets, from their supports, and also from the electrical conductors associated therewith.

Existing lamp sockets of the conventional type are not constructed however to permit ready detachment from their mechanical and electrical connections, and an important object of the present invention is to provide a lamp socket corresponding closely in general 30 appearance and structure with the conventional socket, but adapted for ready disconnection, with the lamp and its shade and other fittings constituting a lighting unit, from the electrical conductors and from the suspending means, whatever the character of 35 the latter may be, as for example a chain, with which the conductor may be associated, or an insulated conductor specially constructed to afford the increasing degree of 40 mechanical strength.

In pursuance of this object, and other important objects of the invention, which are 45 duly illustrated and described herein, I have devised a novel socket having a threaded receptacle of substantially the usual form to 50 receive a lamp or similar article to be screwed

therein, and having the usual, or suitable, electrical contact terminals to co-operate with those on the base of a lamp or corresponding article, my improved socket being provided also with auxiliary electrical contact terminals 55 adapted to co-operate with appropriate contact terminals on a connecter-member connected with the electrical conductors from which the socket derives its supply of current.

In accordance with the invention, the socket is provided also with a mechanical connection, such as a hook, or a bail, (a bail only being shown in Fig. 1, although mechanics skilled in the art will readily understand that the upper loop of the bail may be readily 60 formed into a hook for engagement with overhead supports) by means of which it may be hung upon a supporting chain or with some other readily connectible and disconnectible 65 mechanical device to permit its support in desired position, the mechanical and electrical connections being preferably so positioned relatively to each other that when the lighting unit is removed by unhooking the socket from its supporting chain, or is otherwise disconnected from its support, the user can effect 70 the electrical disconnection by simply pulling the socket away from the terminals of the connecter member, ample room being provided 75 for this operation inside the loop of the bail.

Conversely, the connections may be effected by "plugging in" the electrical connections and hooking the unit on its chain, in a manner 80 easily understood by the average user, and not requiring the services of an electrician.

A further object of the invention is to provide the improved socket with such a removable connecter member, these two parts constituting a unitary structure which can be 85 sold to the user as a complete article of manufacture, and can be installed without special tools, involving no risk in the installation, as the connecter-member can be removed from the socket and connected to the supply conductors first, and is then ready to have the 90 socket terminals plugged in, in the usual manner.

In a modified form of the invention, I have 95 substituted for the socket member a plugging 100

member cooperating with a receptacle member, connectible and disconnectible electrical-
ly by movement in a plane with a wire bail or
loop engaging one of the members and em-
bracing within its loop the other member,
wires for supplying current being engageable
with one member while wires connectible
with the other carry the current to a lamp or
fixture. Either end of the loop or bail is pro-
vided with a hook for engaging with a sup-
port, as a chain. While the other end may be
provided with an eye for receiving a hook.

The invention may be readily understood
from the following description together with
the accompanying drawing wherein:

Figure 1 shows the invention provided with
threaded socket to receive a lamp.

Figure 2 shows the connector members
neither of which is provided with a socket for
a lamp.

Proceeding in accordance with the drawing
of Figure 1, 1 is a socket member formed
usually of porcelain or other suitable mate-
rial being provided with threaded metal,
member 2, as shown by dotted lines for re-
ceiving threadedly a lamp (not shown).
The lamp being provided with a contact for
cooperation with contact 3 which connects
with blade 4. Blade 5 contacting with
threaded member 2 whereby electrical con-
tact is provided with the lamp in the conven-
tional manner. Blades 4 and 5 are adapted
for plugging into receptacle 6 through aper-
tures 7 and 8 and engaging with contacts 9
and 10 to which supply wires (not shown)
are connected as by screws 11, thus complet-
ing the circuit to the lamp.

A shade support or holder 12 may be pro-
vided, which serves to support a reflector glass
globe or the like.

A bail 13 is secured to socket member 1, as
by projecting at its open end through open-
ings in member 1, and being provided with
threaded sections whereby nuts 14 shown in
dotted section engage the ends of the loop and
bear against member 1. The upper or closed
end of the bail is provided as at 15 with an
eye-like section for receiving supporting
means, as a hook from an overhead chain, not
shown. That section of the bail as at 15 may
be formed into a hook for engagement as with
a link of a chain if desired. It will be noted
that the bail is of such length as to provide
conveniently for movement of receptacle 6
within the bail enclosure, to permit of ready
plugging engagement and disengagement of
blades 4 and 5 with contacts 9 and 10, and
that receptacle 6 is of proper proportions as
to be freely movable without contacting with
the bail.

The operation is as follows:

Supply wires are connected by screws 11
to contacts 9 and 10 of receptacle 6 and sup-
port the latter adjacent the lower end of the
overhead support, such as a chain provided

with a hook at its lower end. The contacts
9 and 10 being wholly contained in receptacle
6, no danger of accidental engagement there-
with exists. Socket 1, with bail assembled
and lamp screwed thereinto, may then be
brought into position and blades 4 and 5
plugged into receptacle 6, thus completing
the electrical circuit and the hook not shown
carried by the overhead support, engaged
with the bail. The structure is then in oper-
able assembly. It will readily be seen that to
disassemble the structure, it remains for the
user to merely disengage the hook from the
bail and remove the receptacle member 6 from
engagement with the blades of member 1.

A modified form of the invention is shown
in Figure 11 wherein a bail 13a is provided
at one end with an eye 15a at one end and a
hook 16 at the other, although it will be read-
ily understood that both ends may be formed
as either a hook or as an eye. Supply wires
17 are connected with the contacts of recep-
tacle 6a as with receptacle 6 of Figure I. A
member 18 provided with blades as 4 and 5
of Figure I, for plugging engagement with
receptacle member 6a to complete the electric-
al contacts. Wires 19 carry the current to
the lamp or fixture.

Receptacle member 6a and plug member 18
are similar to those shown in my prior ap-
plication Serial Number 396,213 filed Septem-
ber 30, 1929 which may be referred to for
a more detailed description. Bail 13a en-
gages with receptacle 6a to secure the latter
within the loop section of the bail as by pro-
viding recesses 20 in ribbed section 21 of re-
ceptacle 6a. When plug 18 is engaged with
receptacle 6a it will thereby be secured with-
in the loop of bail 13a. This loop is of suf-
ficient length to provide for the plugging en-
gagement and disengagement of plug 18 with
receptacle 6a therewithin.

Loop 13a may be formed open as at 22 so
it may be sprung open to facilitate the as-
sembly of the loop with receptacle 6a if de-
sired, or closed if preferred.

The operation of this modified form of my
invention is as follows:

Receptacle 6a has supply wires 17 connect-
ed therewith and bail 13a engaged therewith
at the recesses 20 in ribbed section 21. Wires
19 are connected with receptacle 18 and with
the lamp or fixture. A support from the ceil-
ing, not shown, having a hook is engaged
with the eye 15a of the bail. Member 18 is
plugged into engagement with receptacle 6a
by blades 4 and 5, thus establishing the elec-
trical circuit and the fixture or lamp with
which wires 19 connect is engaged by hook
16 at the lower end of the bail. To disassem-
ble, the hook 16 is disengaged from the fixture
and member 18 is disengaged by a single sim-
ple movement from receptacle 6a. Blades 4
and 5 in either form of the invention shown
may be provided with depressions 23 to re-

ceive projections 24 on contacts 9 and 10 of the receptacle whereby to secure the plug and receptacle against accidental or unintentional disengagement.

5 With either of the forms of the invention shown, an extremely strong mechanical support is assured and a structure that is readily connectible and disconnectible both mechanically and electrically.

10 The invention is novel in several respects and possesses utility readily appreciable by ordinary users of electrical lighting fixtures as well as by those skilled in the arts of manufacture and installation of such fixtures.

15 What I claim is:

1. A connector-socket comprising in a unitary structure a connector-member adapted to be connected permanently to electrical conductors; and a lamp socket member provided with means for plugging into said connector member, said connector-socket being further characterized by means extending outside of and over the connector member for mechanically supporting said unitary connector-socket structure, said means comprising a bail mounted rigidly on said lamp socket member.

2. A connector-socket comprising in a unitary structure a connector-member adapted to be connected permanently to electrical conductors; and a lamp socket member provided with means for plugging into said connector member, said connector-socket being further characterized by means extending outside of the connector member for mechanically supporting said unitary connector-socket structure said means comprising a bail mounted rigidly on said lamp socket member and of sufficient length to permit play of said receptacle member therein for connection and disconnection.

3. A two part electrical connector, one of said parts connecting by plugging engagement with the other, whereby to establish electrical connection therewith, one of said parts being supported by a bail member which latter surrounds and projects beyond said other connector part to permit of the plugging and unplugging freely between said parts.

4. An electrical connector device comprising a chain link readily connectible with and disconnectible from other chain links, said first named link surrounding both parts of a two part plugging electrical connector so as to permit of the plugging engagement and disengagement between the parts by movement within the loop along the axis of the link.

5. A connector-socket comprising in a unitary structure a connector-member adapted to be connected permanently to electrical conductors; and a lamp socket member provided with means for plugging into said con-

necter member, said connector-socket being further characterized by means extending outside of the connector member for mechanically supporting said unitary connector-socket structure, said means comprising a bail mounted rigidly on said lamp socket member and of sufficient length to permit play of said connector member therein for connection and disconnection.

In testimony whereof, I have signed this 75 specification.
